ATTORNEY.

UNITED STATES PATENT OFFICE.

HERMAN C. WELTER, OF ROCHESTER, NEW YORK, ASSIGNOR TO HALL-WELTER CO. INC., OF ROCHESTER, NEW YORK.

CHECK PROTECTOR.

Application filed August 23, 1923. Serial No. 659,011.

To all whom it may concern:

Be it known that I, HERMAN C. WELTER, a citizen of the United States, residing at Rochester, in the county of Monroe and 5 State of New York, have invented a new and Improved Check Protector, of which the following is a specification.

The present invention relates to check protectors of the character adapted to mutilate 10 the surface of the paper in such manner as to prevent altering the subject matter written or printed thereon, an object of the invention being to provide an effectively operable device for this purpose which is of simple and inexpensive construction. In accomplishing this, I make use of two impression members movable relatively toward each other to break the surface of the paper held between them, and it is another object of the 15 invention to provide an adjustable means for limiting the movement of these members so as to predetermine the depth of the impression to be made and also to secure a corresponding depression in checks varying in 20 thickness of paper.

Although the device may be used for marking on any portion of a check or draft, it is more especially intended to be employed 25 in conjunction with a check writing machine, the latter printing and mutilating the paper along the amount line while the device is used to mark the paper over the payee's name; and to this end it is a further 30 object of the invention to construct the device as an attachment to a check writer but 35 having it removable and independently operable.

And, a still further object of the invention 40 is to so mark the paper as not to destroy the legibility of the written or printed matter.

To these and other ends the invention consists of certain parts and combinations of 45 parts as will be fully set forth in the following description and particularly defined in the appended claims.

The accompanying drawings illustrating 50 the invention are as follows:

Figure 1 is a top plan view of the check 55 protector.

Fig. 2 is an end view of the device.

Fig. 3 is a fragmentary plan view of the 60 base portion and parts carried thereby.

Fig. 4 is a sectional view on the line 4-4, 65 Fig. 1.

Fig. 5 is a sectional view on the line 5-5, Fig. 1.

Fig. 6 shows a check writing machine in 60 side elevation and the check protector attachment secured thereon.

Fig. 7 is an enlarged sectional detail view of the marking roller and platen.

Fig. 8 shows a fragmentary portion of a 65 check having the amount for which the check is made payable illustrated as printed by a check writing machine, and the payee's name protected by markings on the paper made by a device constructed in accordance with the present invention.

Fig. 9 is a side view in detail of a modification of the invention in which two marking rollers are used.

And, Fig. 10 is a sectional view on the line 10-10, Fig. 9.

In the drawings similar reference numerals refer to similar parts throughout the several views.

The numeral 1 represents a base plate 75 which may be secured to a support in any suitable manner. In the present instance, the support is the upper portion 2 of a check writing machine, such portion being formed with a top wall upon which the base plate rests and side walls. To the end that the base 1 may be firmly clamped to the machine, it is formed on one side with downwardly projecting ears 3 adapted to engage 80 one of the said side walls and on its other side, intermediate the arms 3, with a similar arm 4 threaded to receive a transversely extending screw 5 having a clamping head 6 85 rotatably mounted on its inner end for engaging the other of said side walls, turning of the screw 5 drawing the clamping members toward each other to firmly grip the 90 side walls of the machine head. Non-metallic washers 7 are preferably carried on the under face of the base 1 and the inner faces of the arms 3 and screw head 6 to insure an even bearing for the base plate and prevent 100 marring the surface of the head 2.

At one end of the base plate 1 is a lateral extension 8 formed with upwardly extending ears 9 carrying a pintle 10 on which a lever arm 11 is fulcrumed by having the outer ends of ears 12 pivotally mounted on the pintle, these arms projecting downwardly from the arm 11 and engaging the inner faces of the ears 9 to prevent sidewise movement of the arm. This lever arm 11 ex- 110

tends transversely of the base 1 and is formed on its outer end with a head 13 which acts as a support for a guide extending longitudinally of the base. In the present instance this guide comprises two rods 14—14 having their inner ends projecting through holes therefor in the head 13 and fixed to the head, while their outer ends are rigidly connected by a link 15 removably held in place by screws 16 threaded into the ends of the rods 14, this link being removable to permit placing a carriage 17 on the guide rods.

The carriage or slide 17 is a block having openings therethrough for receiving the rods 14 and whereby the block is slidably supported on the rods, movement of the carriage being back and forth between bumper washers 18 abutting opposed faces of the head 13 and link 15. On the under face of the carriage block 17 are two lugs 19 between which, rotatably mounted on a pin 20 carried by the lugs, is a marking roller 21 which coacts with a fixed bed or platen member 22 comprising a plate secured at its opposite ends by screws 23 to the base plate 1.

Any suitable impression surfaces may be formed on the roller and the platen. I prefer, however, to form on the face of the platen a plurality of alternately arranged and longitudinally extending V-shaped ridges and grooves, and to correspondingly form the surface of the roller with intermeshing ridges and grooves so as to permit coaction of the two members in movement of the roller over the platen. The roller 21 is also grooved axially, the grooves preferably being V-shape, so that its surface presents a plurality of regularly spaced axially extending rows 24 of ridges with the edges of the ridges extending circumferentially of the roller and with the side walls of the axially extending grooves inclined. Thus, when a check is marked by the device the marking will constitute a plurality of longitudinally extending rows of regularly spaced V-shaped depressions in the paper with the spaces and depressions in the several rows aligned transversely. The depth of these depressions 25 may be predetermined by an adjusting means which limits the movement of the roller toward the platen and such adjustment, it will readily be understood, permitting a corresponding depth of depression in papers of various thicknesses, the most satisfactory results being secured by making the adjustment so that the paper at the bottoms of the depressions will be broken. I have found that by marking the paper in this manner the legibility of the writing is not destroyed and that erasure of the writing is made practically impossible without destroying the paper.

The adjusting means, in this instance, is

an adjustable screw 26 threaded through a boss 27 on the lever arm 11 just in advance of the pintle 10, the bottom of the screw engaging the base plate 1 to limit the movement of the roller 21 toward the platen 22, this movement being against the action of a coiled compression spring 28 surrounding the screw 26 and bearing against the lever and base plate. The spring normally holds the lever with the roller away from the platen, as shown in Fig. 2, movement of the lever to inoperative position being limited by a lug 29 extending rearwardly from the lever and engaging a stop 30 in the form of an arm projecting upwardly from the base plate intermediate the ears 9 and in rear of the pintle 10.

In order to properly position and support the check so that the marking will be along a certain line, an elongated plate 31 is secured for lateral adjustment on the base plate 1 in substantially the plane of the platen and is formed with an upwardly extending side flange 32 which acts as a gauge and aligning means for the check, the plate 31 also having a flange 33 bent downwardly over an end of the base 1 and slotted to receive a clamping screw 34 threaded into the base.

When operating the device a check is placed so as to rest upon the platen and the supporting plate 31 with the side edge of the check against the gauge 32, after which the gauge is adjusted to properly position the check relatively to the platen so that the marking will be along a certain line such, for instance, as that on which the payee's name is written. The lever arm 11 is then brought down against the action of the spring 28 by pressing on the knob 35 on the carriage 17 and at the same time the carriage is moved along the guide rods 14 to its outermost position. Further pressure is then exerted on the knob until the ridges on the roller are felt to break through the paper, this additional movement being limited by the adjustable stop 26, the carriage then being moved along the rods 14 to its position against the lever head 13 and under a yielding pressure due to the action of the spring 28 which returns the lever and parts carried thereby to inoperative position when the hand of the operator is released from the knob, the marking effected being as illustrated in Fig. 8 over the name of the payee. While the operator uses one hand on the knob 35 to operate the marking roller, the fingers of the other hand are employed to hold the end of the check firmly against the extended table portion 36 of the base 1.

In Figs. 9 and 10 there is shown a modification of the invention in which a carriage 37 movable on guide rods 51 carries two marking rollers 38 and 39 which coact with

respective platens 40 and 41 to mark a check along two lines such as that on which the payee's name is written and the one bearing the amount for which the check is 5 made payable. These rollers 38 and 39 are placed preferably one in advance of the other and each is mounted on a pin 42 carried by ears 43 formed on a slide member 44 movable transversely of the carriage in a 10 guide-way 45 by means of an adjusting screw 46 threaded into the carriage and held against axial movement by a pin 47, these screws being operable from opposite sides of the carriage to effect lateral adjustment of the rollers.

It might be added that the head portion 2 of the check writing machine is mounted upon a base 48 over which the check is fed and that the printing is done by the coaction 20 of a platen 49 supported in the base and type on a carrier, not shown, mounted for movement in the head 2 and controlled in its movement toward and from the platen 49 by the operating crank 50.

25 What I claim is:

1. In a check marking device, a platen formed with a plurality of parallel extending ridges and grooves, a roller movable over said platen and formed with a surface 30 mating with said ridges and grooves, the surface of the roller also being formed with regularly spaced axially extending grooves, and a support for the roller.

2. In a check marking device, a platen 35 formed with a plurality of parallel extending V-shape ridges and grooves, a roller movable over said platen and formed with a plurality of regularly spaced axially extending rows of ridges and grooves, these 40 ridges and grooves extending circumferentially of the roller and mating with those of the platen, and a support for the roller.

3. In a check marking device, a platen 45 formed with a plurality of parallel extending V-shape ridges and grooves, a roller movable over said platen and formed with a plurality of regularly spaced axially extending rows of ridges and grooves, these 50 ridges and grooves extending circumferentially of the roller and mating with those of the platen, a support for the roller, and adjustable means for limiting the movement of the roller into coacting engagement with the platen.

55 4. In a check marking device, a platen formed with a plurality of parallel extending ridges and grooves, a roller movable over said platen and formed with a surface 60 mating with said ridges and grooves, the ridges and grooves of one of said members being intersected by regularly spaced transverse grooves, and a support for the roller.

5. In a check protector, a platen, a guide 65 movable toward and from the platen, a carriage movable on the guide longitudinal-

ly of the platen, a roller mounted on the carriage for coaction with the platen, spring means for returning the guide and parts carried thereby to inoperative position and whereby the roller may be yieldingly held 70 during its movement over the platen.

6. In a check protector, a platen, a guide movable toward and from the platen, a carriage movable on the guide longitudinally of the platen, a roller mounted on the carriage for coaction with the platen, 75 said platen and roller having intermeshing serrated surfaces, spring means for returning the guide and parts carried thereby to inoperative position and whereby the roller may be yieldingly held during its movement over the platen, and adjustable means for limiting movement of the roller into engagement with the platen.

7. In a check protector, a base, a platen on the base, a pivotally supported arm movable in a plane transversely of the platen, a guide carried by said arm, a carriage movable on said guide, a roller mounted on the carriage for coaction with said platen, the 80 platen and roller having intermeshing serrated surfaces, adjustable means for limiting movement of the roller into coacting engagement with the platen, spring means for carrying said arm and parts carried 85 thereby to inoperative position and whereby the roller may be yieldingly held in its movement over the platen, and a stop for arresting said arm in its inoperative movement.

8. In a check protector, a base, a platen 90 on the base, an arm pivotally connected to the base and movable in a plane transversely of the platen, a guide comprising two spaced rods extending from said arm and parallel with said platen, a hand operated carriage 95 movable on said rods, a roller mounted on the carriage for coaction with the platen, said platen and roller having coacting paper marking surfaces, an adjustable stop for limiting movement of said arm in one direction, a stop for arresting the arm in its movement in the opposite direction, and spring means for normally holding the arm 100 in inoperative position.

9. In a check protector, a base, a platen 110 on the base, a lever arm fulcrumed on the base, stops on opposite sides of the fulcrum for limiting movement in opposite directions of said arm, one of the stops being adjustable, spring means for normally holding the arm against the other of said stops, a guide extending from said arm and in the direction of said platen, a carriage movable on said guide and removable therefrom, and a roller mounted in said carriage, the platen 115 and roller having coacting paper marking surfaces.

10. The combination with a check writing 120 machine having a frame portion, of two members movable relatively toward and 125

- from each other, one of said members comprising a base removably secured to the said frame portion, and the other member comprising a lever arm fulcrumed on the base 5 and movable in a plane transversely thereof, stops on opposite sides of said fulcrum for limiting movement of the arm in opposite directions, one of said stops being adjustable and comprising a screw carried by one 10 of said members and adapted to engage the other member, a coiled compression spring encircling said screw, a platen extending longitudinally of said base, a guide carried by said arm, a carriage movable on the 15 guide parallel with said platen, and a roller mounted on the carriage for movement back and forth over the platen, said platen and roller being formed with coacting paper marking surfaces.
- 16 11. The combination with a check writing machine having a frame portion, of a base member and means carried thereby for removably clamping it to the said frame portion, ears on said base, a stop on the 20 base intermediate and in rear of said ears, a pintle mounted in said ears, an arm movable in a plane transversely of the base and fulcrumed on the base by having ears projecting downwardly therefrom pivotally 25 mounted on said pintle, an adjustable stop screw threaded through said arm in front of said pintle and adapted to engage said base to limit movement of said arm in one direction, while said first named stop limits 30
- movement of the arm in the opposite direction, a coiled compression spring encircling said screw, a guide comprising two spaced rods carried by said lever arm, a platen on the base parallel with said rods, a removable connector for the outer ends of the rods, a carriage movable on the rods, a roller mounted on the carriage for movement over the platen, the platen and roller being formed with coacting paper marking surfaces, and a handle on the carriage for controlling both the movement of the lever arm and operation of said roller. 35
12. In a check protector, a base, a guide movable toward and from the base, a carriage movable along said guide, a plurality 40 of slides supported on the carriage and movable transversely thereof, a roller mounted in each of said slides, and means for effecting independent adjustment of each of the slides, the base and the rollers 45 being formed with coacting paper marking surfaces. 50
13. In a check protector, a base, a guide movable toward and from the base, a carriage movable along said guide, a plurality 55 of slides supported on the carriage one in advance of the other and movable transversely of the carriage, a roller mounted in each of said slides, and an adjusting screw 60 for each of the slides, the base and the rollers being formed with coacting paper marking surfaces. 65

HERMAN C. WELTER.
